Application April 8, 1949, Serial No. 86,174

15 Claims. (Cl. 122—328)

1

This invention relates to a steam generating installation of the water tube type.

The invention, more particularly, relates to a water tube steam generator adapted for operation at high capacities and high steam pressures and for the effective use of pulverized fuel in the furnace of the installation.

The steam generator of the invention is particularly adapted for the efficient generation of steam at high capacities, with effective use of minimum space requirements for the furnace and the convection components of the installation, these characteristics making the steam generator advantageous for use in a locomotive.

The steam generator of the installation involves a water cooled furnace used in conjunction with steam generating water tubes, some of which form the boundary walls of the furnace which is particularly adapted for the burning of pulverized coal as fuel.

In the interest of high ignition temperatures, and of complete combustion of fuel, high furnace temperatures are maintained in the primary or high temperature zone of the furnace. The combustion of the coal in this zone results in the liberation of ash which is raised to a temperature above its fusion point or the fusion point of any of its several constituent chemicals. Consequently, the individual particles of molten ash or slag, and larger particles resulting from the coalescing of several individual particles exist in suspension in the gases in the high temperature zone of the furnace and, somewhat beyond that zone. Some of these particles contact the furnace boundary surfaces and adhere thereto. They are at first chilled and solidified by the proximity of the cooler surfaces of the water tubes of the furnace, the lower temperatures of these tubes being maintained by fluid circulated through them. As a stratum of this chilled slag is built up from the wall surface, a condition is ultimately reached which, due to the thermal resistance of the layer so formed, and due to the high temperature existing in the furnace, results in the surface stratum which normally remains at the fusion temperature of the slag. Additional particles are deposited thereon in molten condition, flow down the surfaces of the stratum on the furnace walls and, at high capacities, result in a considerable flow of molten ash to the furnace floor. This flow of excess molten ash is, in the illustrative installation continuously disposed of so as to prevent such an accumulation which would interfere with the efficient operation of the furnace.

2

Other particles of molten slag remain in suspension in the gases as they flow from the furnace and through succeeding gas passages. Some of these remaining particles contact the walls of

5 these passages which, in the illustrative installation, are formed by heat absorbing fluid conducting tubes. Under these conditions heat is radiated from the suspended particles as well as from the gases in which the particles are suspended. 10 This heat is radiated to the walls and is absorbed and the degree of radiation and absorption varies with the temperature differential between the particles and the heat receiving wall surfaces. Also, this differential is, in turn, dependent upon the cleanliness of the wall surfaces, or the freedom of those surfaces from slag accumulation and the attendant thermal resistance and higher surface temperatures caused thereby.

15 Some of these conditions are beneficial to one stage of the combustion and heat absorption process, but, are detrimental to other stages. In the stage or zone where combustion is taking place there are important advantages resulting 20 from the high temperature of the furnace boundary surfaces. Examples of such advantages are the expedition and the completion of combustion. In stages or zones beyond the primary combustion zone, and after substantially complete combustion is effected, the major consideration is a high rate of heat absorption. This necessitates boundary walls at relatively low temperatures in order to effect high temperature differentials between the water or other fluid 25 cooling the walls, and the combustion components transmitting heat thereto.

30 The present invention contemplates a steam generator which utilizes a convection section and a furnace gas tempering section in combination 35 with a furnace, all operating in such a manner as to effectively meet the above indicated conditions and operating with a high availability factor under different conditions such as those involved by the use of coals from different sources. Coals from different seams or different sources used in pulverized form in furnaces all contain ash in greater or lesser amounts and the ashes from the different coals not only differ in chemical constituency but also differ in fusion 40 temperatures.

45 One object of the invention is to provide a steam generating installation in which combustion gases and their suspended solids are effectively cooled after they leave the high temperature zone of the furnace and before they reach 50

55

the heat absorption zone formed by the spaced tubes of the convection section. Such tempering action is associated with means providing for the elimination of the cooled ash solids separated in the tempering zone, both of these actions preventing the tubes of the convection section from receiving such accumulations of ash that they would soon become covered thereby to such an extent that the installation would lose its optimum steam generating capacity as a result of the closing of the gas passages between adjacent tubes.

The invention will be described with reference to an illustrative embodiment shown in the accompanying drawings, and further objects of the invention will appear as the description proceeds.

In the drawings:

Fig. 1 is a longitudinal vertical section through the illustrative installation;

Fig. 2 is a partial sectional plan, or horizontal section, on the line 2-2 of Fig. 1. This view shows only part of the installation involving the high temperature zone of the furnace and the gas tempering section of the installation immediately adjacent the furnace and receiving furnace gases directly therefrom;

Fig. 3 is a partial sectional plan complementary to Fig. 2, taken on the same plane as Fig. 2 and showing the arrangement of the elements of the convection section, rearwardly of the gas tempering section shown in Fig. 2;

Fig. 4 is a vertical section on the line 4-4 of Fig. 1 and looking in the direction of the arrows. This figure shows the arrangement of the steam generating tubes delineating the walls, roof, and floor of the high temperature section of the furnace;

Fig. 5 is a vertical section on the multiple plane line 5-5 of Fig. 1, looking in the direction of the associated arrows and with parts of some of the tubes 65-87 being omitted for the sake of clarity;

Fig. 6 is a vertical section through the installation on the line 6-6 of Fig. 1, indicating the construction of the superheater;

Fig. 7 is a transverse vertical section on the line 7-7 of Fig. 1, showing the construction and arrangement of the tubes for the main bank 14 of steam generating tubes;

Fig. 8 is a transverse vertical section on the line 8-8 of Fig. 1 showing the arrangement of the more closely spaced tubes of the screen section, immediately rearwardly of the screen section illustrated in Fig. 9;

Fig. 9 is a transverse vertical section on the line 9-9 of Fig. 1 showing the arrangement of the more widely spaced screen tubes disposed just forwardly of the screen tubes shown in Fig. 8;

Fig. 10 is a multiple plane transverse vertical section on the line 10-10 of Fig. 1 showing the floor continuations of the wall tubes just forwardly of the lower ends of the tempering fluid ducts; and

Fig. 11 is a transverse vertical section on the line 11-11 of Fig. 1 showing the wall cooling tubes of the front transverse wall of the furnace and also showing the arrangement of the burner tubes relative to the steam and water drum and relative to the roof of the furnace.

The steam generator shown particularly in Figs. 1, 2 and 3 involves a furnace 10, the walls of which are defined by steam generating tubes connected at their upper ends to the steam and water drum 12. The steam and water drum

(which may also be termed an upper fluid chamber) extends over the furnace gas tempering section disposed immediately rearwardly of the furnace 10, and beyond the gas tempering section the drum extends over the convection section which includes the main bank 14 of steam generating tubes, and the superheater 16. The furnace is fired by burners such as those indicated at 20-25. These are pulverized fuel burners supplied with a mixture of fuel and primary air through tubes such as those indicated at 26 and 27.

In the operation of the installation, the flames from the burners 20-25 impinge against a stratum of molten slag upon the rearwardly inclined furnace floor 30, the floor being formed by the floor tube sections such as those indicated at 32 and 34 of Fig. 4, and their refractory covering 36. The combustion products then pass rearwardly from the high temperature zone of the furnace and between the upright shadow tubes such as those indicated at 40-45 in Figs. 1 and 2. Each of these shadow tubes has a refractory covering such as that indicated at 46. The upper ends of these tubes are directly connected to the steam and water drum 12 and their lower ends are connected to headers which are in turn connected to the drum 12 by appropriate down-comers to be later referred to.

As the furnace gases contact the shadow tubes, some of the molten ash particles suspended in the gases gather upon the refractory coverings of these tubes and flow downwardly along those surfaces to the rearwardly inclined extension 41 of the furnace floor, this extension directing the particles to a slag outlet opening 43 above a slag disposal zone. Accumulations of slag upon the surfaces of the tube refractory covering forming the margins of this outlet are periodically removed by the operation of the swinging element 49 (Fig. 1) pivoted at 50 and connected to a fluid pressure cylinder 53 by a link 54. This cylinder is pivoted at its forward end to a fixed bracket 55.

After passing the shadow tubes 40-45 the gases are caused to flow through the tempering passages 60 and 61 (Figs. 4 and 10). These passages are formed between spaced groups of inclined steam generating tubes such as 65-87, the groups of these tubes forming downwardly inclined ducts 92-94 (Fig. 2) for movement of a tempering fluid such as steam or air, transversely of the passages 60 and 61. Some of these tubes form the central duct 93, and the remainder of the tubes form the remaining lateral ducts 92 and 94 for the tempering fluid. This fluid passes to these ducts from appropriate tubular connections or ducts. The fluid then passes horizontally into and across the tempering passages 60-61 through upright slots or openings such as 98, 99, 100 and 101 (Fig. 2) to lower the temperature of the furnace gases and their suspended solids and thereby cause the solids to coalesce for downward separation from the gases in the tempering zone. This zone may be considered as part of a slag separation zone extending rearwardly from the shadow tubes to a position rearwardly of the tempering ducts.

The tempering fluid is distributed to the ducts 92, 93, and 94 from a transverse duct 458 (Fig. 1) which is formed by the upper parts of the shadow tubes, the tubes forming the walls of the ducts 92-94, and the roof of the installation. The upper ends of the shadow tubes are bent so as to extend rearwardly between the tubes forming the ducts, as indicated in Fig. 1. There is thus

formed a transverse tempering fluid passage connecting the top ends of the three tempering fluid ducts. The passage is in communication with an appropriate source of tempering fluid. It is also to be noted that the transverse tempering fluid passage 450 is formed in the space directly beneath the unprotected portion of the steam and water drum. This permits the tempering fluid, such as air, to pass between the roof tubes from the air duct 451 passing alongside the drum, see Figs. 4 and 5.

The tubes 65—87 forming the tempering fluid ducts are connected at their lower ends to a transverse header 105 integrally joined at its ends to the side headers 162 and 164 which are appropriately connected by downcomers to the water space of the steam and water drum 12. The upper ends of the tubes 65—87 are connected directly to the steam and water drum 12 as indicated in Fig. 4.

The middle duct 93 for tempering fluid has its front wall formed by the steam generating tubes 76—81, the spaces between these tubes being closed by a non-metallic refractory covering such as that indicated at 110. This refractory material is installed in a semi-plastic condition over the forward surfaces of the tubes and preferably between radial metallic studs welded to the tubes. This construction is well known in the art as a stud tube wall. These tubes are also so arranged that the wall presents a concave face toward the oncoming gases. The tubes 70—75 delineating the rear wall of the middle duct 93 are similarly arranged. This wall is also a stud tube wall including the refractory material 112. This wall is so spaced from the front wall of the duct that on one side the narrow upright slot 100 is formed for the discharge of tempering fluid across the flow of furnace gases and other products of combustion through the passage 60. At the other side of the duct 94 is a similar slot 99 for the flow of tempering fluid to combustion products in the tempering passage 61.

The tempering fluid duct 92 at the outer side of the passage 60 and opposite the slot or opening 100 is similarly formed by stud tubes 65—69 and space closing refractory material as indicated at 116 and 118 to present an upwardly inclined slot or opening 101 for tempering fluid flow into the stream of combustion products flowing rearwardly through the passage 60. In like manner, the duct 94, at the opposite furnace wall of the installation is formed by similarly arranged stud tubes 82—87, with the spaces between these tubes closed by a refractory material indicated at 120 and 122. The discharge slot 98 for tempering fluid flow across the passage 61 is formed between the tubes 82 and 87.

The forward walls for the tempering fluid ducts 92 and 94 also present concave faces forwardly toward the oncoming combustion products, the marginal tubes 87 and 67 being disposed forwardly of the remainder of these walls to provide forwardly facing rims, or marginal surfaces, similar to those provided by the tubes 76 and 81 for the forward wall of the middle gas duct 93.

Directly rearwardly of the tempering passage 61 is a platten 126 formed by the forwardly inclined portions of the tubes 130—135. The upper ends of these tubes are directly connected to the steam and water drum 12 and their lower ends are appropriately connected into the fluid circulation of the installation. The platten terminates at the position indicated in Fig. 1 at 139. To provide this construction, the lower parts of

tubes 135, 133 and 131 are bent to extend outwardly to the wall tubes 135A and 131A (Fig. 2) to which they are joined by welding. The remaining platten tubes are welded to these bent lower ends at 130A, 132A, and 134A.

A platten 140, similar to the platten 126, above described, is disposed directly rearwardly of the passage 60. It is formed by similarly arranged tubes 141—146 and they are similarly connected into the fluid circulation of the installation. The tubes of the plattens 126 and 140 are substantially contiguous and they form radiant heat shields and gas flow deflectors between the furnace 10 and the tubes of the widely spaced screen 150 (Figs. 3 and 9) and the more closely spaced tubes of the secondary screen 152 (Fig. 8) disposed at the entrance of the convection section. The plattens divide the chamber between the screens 150—152 and the tempering passages 60 and 61 into two zones, the rearward zone being free of the tubes, to promote the separation of ash and the collection of solidified ash in a subjacent ash disposal zone.

After passing the widely spaced tubes of the screen 150 and the tubes of the succeeding screen 152, the furnace gases pass through the flow equalizing space 154 just forward of the superheater 16.

The tubes of the screen 150 are connected at their lower ends to a header 160 and their upper ends are in communication with the steam and water drum 12 (Fig. 9). The header 160 preferably communicates directly at its opposite ends with the lower side wall headers 162 and 164. These headers are indicated in Fig. 3, as terminating just rearwardly of the header 160 but they are connected to the rearward headers 166 and 168 by tubular connections 170 and 172.

The bank of tubes constituting the tubular screen 150 is three deep as indicated particularly in Fig. 3 of the drawings. There is a front row of tubes such as 150A, an intermediate transverse row of tubes such as 150B, and a rear row of tubes 150C. Each of these tubes is directly connected at its upper end to the steam and water drum (or upper fluid chamber) 12 and the vertical lower portions of the tubes 150B and 150C are weld connected to the rearwardly inclined lateral portion 150D of each of the front tubes 150A. Such connections are provided at the positions indicated at 150F and 150H, in Fig. 1. Thus, the water supply for the tubes 150B and 150C is afforded by their connections to the inclined lateral 150D which, in turn, is directly connected to the lower transverse header, or lower fluid chamber, 160, in the arrangement particularly indicated in Fig. 1. The inclined laterals 150D are shown as connected to the side of the header 160, while the upper part of this header is directly connected to the upright tubes of the screen 152.

The side headers 162 and 164 are also integral with a furnace front wall transverse header 161 (Figs. 1 and 11) from which the front wall cooling tubes such as 163 and 165 extend upwardly to the drum 12, in the arrangement specifically shown in Fig. 11.

The more closely spaced tubes of the screen section 152 are vertically disposed directly above the header 160, as indicated in Figs. 3 and 8. Some of these tubes such as 180—182, are united by welding with other tubes of this screen section, such as 184—186, in quasi-bifurcated tube constructions to provide an adequate number of tubes in the screen 152 without necessitating an

excessive number of tube seats in the drum 12 at the position of this screen section.

The superheater

The superheater 16 consists of a bank of vertically arranged tubes as indicated in Figs. 3 and 6. These tubes may be described as of the inverted U type. For example, one of these tubes is indicated as having an inlet portion 200 directly connected to the superheater inlet header 202 at the right hand casing wall 204, as indicated in Fig. 6. Beyond the section 200 this tube continues in an upward section 204 to a position 206 centrally of the gas pass. From this position it continues outwardly and then downwardly in an extension 208 leading to a downwardly inclined section 210 which is directly connected to the outlet header 212. The remaining tubes of the superheater are similarly arranged with the two rows of outer tubes such as indicated at 214 and 216 in Fig. 6 having their ends directly communicating with the superheater headers 202 and 212.

It will be understood that there are opposite rows of headers similar to those shown at 202 and 212. The first header, similar to the header 202, in the row at the right hand side of the installation, as it appears in Fig. 6, receives steam through the superheater inlet connection 220 (Fig. 3) and the steam flows from this header through a transversely disposed platten of superheater tubes having components similar to 200, 204, 208, 210, 214, and 216 to the first header (remote from the observer) in the row of superheater headers similar to the header 212, and disposed at the left hand side of the installation. The steam flows from this first left hand header through connections which directly join it to the adjoining header (in the same row) toward the observer. From that header steam flows through another platten of superheater tubes to the second header on the opposite (or right hand) side of the installation. The steam flow continues from one side of the installation to the other and through successive plattens of superheater tubes to the superheater outlet header 202. From that header the steam flows through a plurality of tubular outlet connections such as 222-225 to a header 226. From this header superheater the steam flows to a point of use.

The main bank of steam generating tubes of the convection section

The main bank 14 of upright tubes of the convection section is illustrated in horizontal section in Fig. 3 and in vertical section in Fig. 7. These tubes are L shaped tubes with some of them having their lower portions such as 230-233 directly connected to the lower side wall headers 166 and 168. The upper portions 230A-233A of the same tubes are upright, as shown, and are directly connected to the drum 12. These tubes are supplied with water from the drum 12 by rows of large diameter downcomers such as 240-249. These downcomers are directly connected at their lower ends by headers 166-168 and similarly connected at their upper ends by tubular sections such as 250 and 252, to the drum 12.

The remaining tubes of the bank 14 have their lower and upwardly inclined parts such as 260-263 directly connected to the lower ends of the downcomer tubes such as 240-245. From these portions their vertical continuations such

as 272-273 continue upwardly to points of direct connections to the steam and water drum 12.

The rearward ends of the headers 166-168 are directly connected by a cross header 280 and from a central position the downcomer tubes 282 and 283 lead upwardly from the header 280 to the water space of the drum 12.

After flowing over the tubes of the bank 14, the furnace gases flow over the upright bank of airheater tubes 390. These tubes are connected to appropriate inlet and outlet chambers such as that shown at 302 and 302A. Rearwardly of the bank of airheater tubes 390 is a bank of economizer tubes 304. These tubes are shown as U tubes rows of which are connected at their lower ends with successive transverse headers 306-313 and header connections such as 316 for the series flow of feed water through the economizer. The last of these headers forms the outlet header of the economizer suitably connected to the steam and water drum 12 for a supply of feed water thereto.

The slag pan construction

25 The slag disposal opening 48 in the gas tempering zone is formed between a floor extension 330 and a rearward floor section 332, these floor sections consisting of transverse floor tube extensions such as 331 and 333 (Fig. 10) covered by refractory material 335 and appropriately connected to the headers 162-164.

Fig. 5 shows the furnace wall and floor constructions in the transverse zone of the slag tap opening 48. Here, the wall tubes, such as 346 and 347 have reversely bent floor extensions such as 348 and 349, the lower parts of these extensions being directly joined with the headers 162 and 164 in the manner shown.

Slag particles directed downwardly to the slag opening 48 by the forwardly concave walls of the tempering fluid ducts 92, 93, and 94 pass downwardly through that opening into a slag pan construction generally indicated at 334. This construction is secured to the framework or the setting of the installation which includes the railway frame components such as the longitudinal and transverse elements 348-345 (Fig. 1). The car frame including these elements has its central portion offset downwardly between the 50 railway trucks 376 and 371 to advantageously provide a lower center gravity for the installation and effective space for the steam generating components.

The slag pan 334 may be appropriately supplied with a cooling fluid so that the particles of slag entering the pan are solidified in granular form to facilitate their periodic removal. It is also provided with side closures such as 372 and 373 (Fig. 10) for access and for slag removal.

Continuous slag flow through the opening 48 is promoted by the provision for the flow of combustion gases from the furnace through the opening and the slag disposal zone therebeneath. For this purpose a longitudinally extending duct 400 (Figs. 1 and 10) is disposed at the side of the installation. The inlet of this duct is shown in Fig. 10 at 402 as communicating with the slag pan 334, and the outlet of the duct is shown at 404 in Fig. 1, just forwardly of the airheater 390. The duct is also provided with a damper 408 to regulate gas flow through opening 48.

The remaining ash disposal constructions include ash receiving chambers such as 350-353 having side openings provided with the closures 360-364 through which access may be had to

the chambers for periodic removal of ash therefrom:

The particular arrangement of the vertical junction headers such as 202 and 212 (Fig. 6) and the construction and arrangement of the tubes and lower headers 166 and 168 of the steam generating bank of tubes 14 (Fig. 7), are such as to promote the deposition of combustion solids in the ash receiving chambers 362-364 by avoiding obstructions to the falling of solids into the chambers.

While in accordance with the provisions of the statutes we have illustrated and described herein the best form of our invention now known to us, those skilled in the art will understand that changes may be made in the form of the invention covered by our claims, and that certain features of our invention may sometimes be used to advantage without a corresponding use of other features.

What is claimed is:

1. In a fluid heat exchange installation, a furnace having its boundary surfaces defined by fluid conducting tubes, burners, means supplying pulverized fuel and air to the burners which fire the furnace at temperatures above the fusion temperature of the non-combustible residue of the fuel, said boundary surfaces including a floor receiving said residues to form a molten slag layer, the furnace floor being provided with a slag discharge opening, and a slag clearer including a member normally disposed out of the path of falling slag but periodically movable into and upwardly through said slag discharge opening to clear away solidified slag which tends to close said opening.

2. A pulverized coal fired water tube steam generator of restricted vertical and transverse dimensions characterized by having at longitudinally successive positions, a downwardly fired combustion chamber, means presenting water cooled slag contacting surfaces defining a molten slag separation zone and including a transverse row of individually spaced shadow tubes, means including steam generating water tubes arranged to form a tempering gas duct for the introduction of tempering fluid stream into mixing relationship with the furnace gases, means providing a furnace gas pass in which said shadow and duct tubes are exposed, and convection steam generating and superheating surfaces arranged beyond the slag separation zone in the direction of gas flow, the steam generating surfaces being presented by upright tubular elements connected into fluid circulation of the generator and the shadow tubes having their upper ends bent so as to cooperate with the steam generating tubes in forming a transverse tempering fluid passage from which fluid passes to the tempering fluid duct.

3. In a steam generator, a horizontally elongated and vertically restricted primary furnace, a fuel burning system including a set of fuel burners downwardly firing the furnace at high combustion rates with an ash forming solid fuel, fluid cooled tubes defining the floor and other boundaries of the furnace, the furnace floor having a slag discharge opening to which molten slag may flow from a position beyond the burners, the fuel system with its burners being so co-ordinated with the furnace floor that flames from the burners impinge upon a molten ash or slag stratum on the floor, a convection section heated by the furnace gases, means providing for the solidifying of slag particles in gas sus-

pension before the gases pass to the convection section, said last named means including vertically inclined steam generating tubes constructed and arranged to form furnace gas passages with ducts at opposite sides thereof, vertically inclined shadow tubes disposed forwardly of said gas passages, and means supplying said ducts with a tempering fluid which is injected into and mixed with the furnace gases.

10 4. In a steam generator, a horizontally elongated and vertically restricted primary furnace, steam generating tubes delineating the floor and other boundary surfaces of the furnace, a fuel burning system including a set of pulverized fuel burners downwardly firing the furnace at high combustion rates with an ash forming solid fuel, the furnace floor being inclined downwardly away from a position opposite the burners for the flow of molten slag away from that position, forwardly inclined and refractory covered steam generating shadow tubes extending across the gas outlet of the furnace, such shadow tubes being individually spaced transversely of gas flow, other upwardly and forwardly inclined steam generating tubes extending across the flow of gases and connected into the fluid circulation system of the installation, said last mentioned tubes being constructed and arranged to provide tempering fluid ducts through which a tempering fluid passes for mixture with the furnace gases and consequent cooling of the ash particles suspended in the furnace gases, means at the lower part of the installation for receiving solidified ash particles deposited from the furnace gases, and a steam generating convection section disposed rearwardly of the above mentioned tubes.

5. A pulverized coal fired water tube steam generator of restricted vertical and transverse dimensions characterized by having at longitudinally and horizontally successive positions, means forming a downwardly fired combustion chamber, means including tubes presenting water cooled slag collecting surfaces defining a molten slag removal zone, means including steam generating water tubes arranged to form tempering fluid ducts for the introduction of steam into mixing relationship with the stream of furnace gases leaving the slag removal zone, individually spaced shadow tubes disposed across furnace gas flow forwardly of the point of introduction of the tempering fluid, and means presenting convection steam generating and superheating surfaces arranged beyond the slag removal zone in the direction of gas flow, the shadow tubes having their upper ends bent so as to cooperate with the steam generating tubes in forming a transverse tempering fluid passage from which fluid passes to the tempering fluid duct.

6. A steam generator including apparatus for conditioning the products of combustion of pulverized coal flowing rearwardly in a gas pass from a high temperature furnace to a convection section including spaced fluid heating tubes, said apparatus including a water cooled furnace having a floor normally covered with molten ash from the combustion of the coal, a tempering fluid system including fluid cooled ducts for introducing and mixing a tempering fluid with the stream of furnace gases, said ducts being inclined and extending upwardly and forwardly of said gas pass and through the furnace gases and having elongated longitudinally narrow tempering fluid discharge ports opening toward the stream of furnace gases, and individually spaced shadow tubes connected into a fluid cir-

11

culation system and disposed forwardly of said fluid cooled ducts, the shadow tubes having their upper ends bent so as to cooperate with the steam generating tubes in forming a transverse tempering fluid passage from which fluid passes to the tempering fluid duct.

7. Apparatus for conditioning products of combustion of pulverized coal flowing rearwardly in a gas pass from a high temperature furnace to a convection section including spaced fluid heating tubes, said apparatus including a water cooled furnace having a floor over which a slag stratum flows to a slag discharge opening, a tempering fluid system including fluid cooled ducts for introducing and mixing a tempering fluid with the moving furnace gases, said ducts being inclined upwardly and forwardly of said opening through the furnace gases and having elongated longitudinally narrow tempering fluid discharge ports opening toward the stream of furnace gases, and spaced shadow tubes inclined in a manner similar to that of the ducts and disposed in a transverse zone spaced forwardly of the ducts.

8. In a water tube steam generator, a primary furnace having means associated therewith for burning pulverized fuel at furnace temperatures above the fusion temperatures of the noncombustible in the fuel, the primary furnace having a horizontal extension formed by wall cooling steam generating tubes, groups of forwardly inclined steam generating tubes connected into the circulation of the generator and arranged to present a furnace gas cooling barrier across the furnace with an opening between the groups of tubes for the exit of furnace gases, said groups of tubes being also arranged relative to other similarly disposed tubes to form tempering fluid ducts of relatively large free flow area extending into the furnace and having tempering fluid ports laterally of said passage, means for supplying said ducts with tempering fluid for flow of that fluid through said ports into mixing relationship with the furnace gases flowing through said passage, a group of vertically inclined and individually spaced fluid cooled shadow tubes disposed transversely of the extension of the primary furnace at a position forwardly of said passage, an upright platten consisting of a plurality of upright steam generating tubes in contiguous relation and installed directly rearwardly of the gas passage between the tempering fluid ducts, said platten acting as a target wall to catch sprays of slag shot and acting to shield subsequent heat absorbing surfaces from the primary furnace, and a convection section including a bank of steam generating tubes and a convection superheater disposed rearwardly of said platten.

9. In a fluid heat exchange installation, a furnace having its boundary surfaces defined by fluid conducting tubes, burners, means supplying pulverized fuel and air to the burners for firing the furnace at temperatures above the fusion temperature of the non-combustible residue of the fuel, said boundary surfaces including a floor receiving said residues to form a molten slag layer, the furnace floor being provided with a slag discharge opening, a slag receiver beneath said opening, a slag clearer normally disposed out of the path of slag moving downwardly through said opening, and means for periodically moving the clearer upwardly through said slag discharge opening to clear away solidified slag which tends to close said opening.

12

10. In a steam generator, a longitudinally extended elevated steam and water drum, a furnace beneath the drum, wall means providing a gas pass leading from the furnace and disposed beneath the drum, a bank of upright steam generating tubes exposed to the furnace gases in said gas pass, superheater tubes of inverted U-shape disposed within the gas pass and nested to form a bank of spaced tubes, inlet header means disposed at one side of the gas pass out of the path of the furnace gases and connected with the corresponding ends of a plurality of the superheater tubes, and outlet header means disposed at the other side of the gas pass out of the path of the furnace gases and connected to the corresponding outlet ends of the plurality of superheater tubes.

11. In combustion and fluid heat exchange apparatus, means providing a flow of furnace gases with solids in suspension therein, upright tempering fluid ducts extending across said flow in a direction oblique to the direction of the flow, means for supplying said duct with a tempering fluid at a temperature lower than that of said flow or the solids in suspension therein, and individually spaced fluid cooled shadow tubes disposed transversely of said flow and forwardly of said ducts, said ducts having side outlets for the discharge of the tempering fluid into said flow, the upper ends of the shadow tubes being so bent as to co-act with other elements including the walls of said ducts to form a transverse inlet passage or chamber from which the tempering fluid flows to said ducts.

12. Apparatus for conditioning products of combustion of pulverized coal flowing horizontally in a gas pass from a high temperature furnace to a convection section including spaced fluid heating tubes, said apparatus including a water cooled furnace having a floor over which a slag stream flows to a slag discharge opening, a tempering fluid system including fluid cooled ducts for introducing and mixing a tempering fluid with the horizontally flowing stream of furnace gases, said ducts being inclined and extending upwardly and forwardly from said opening through the furnace gases and having elongated longitudinally narrow tempering fluid discharge ports opening toward the stream of furnace gases, and rearwardly and downwardly inclined fluid cooled shadow tubes disposed transversely of said flow of combustion products and at a position forwardly of said ducts.

13. In a water tube steam generator, a primary furnace having means associated therewith for burning pulverized fuel at furnace temperatures above the fusion temperatures of the non-combustible in the fuel, the primary furnace having a horizontal extension formed by wall cooling steam generating tubes, groups of forwardly inclined steam generating tubes connected into the circulation of the generator and arranged to present a furnace cooling barrier across the vertical extent of the furnace with an opening between the groups of tubes for the exit of furnace gases from the furnace, said groups of tubes being also arranged to form tempering fluid ducts of relatively large free flow area extending into the furnace and having tempering fluid ports at the sides of said passage, means for supplying said ducts with tempering fluid for flow of that fluid through said ports into mixing relationship with the furnace gases flowing through said passage, a group of vertically inclined and individually spaced fluid cooled shadow tubes across the

extension of the primary furnace at a position forwardly of said passage, an upright platten consisting of a plurality of upright steam generating tubes in contiguous relation and installed as a canopy directly rearwardly of the gas passage between the tempering fluid ducts, said platten acting as a target wall to catch sprays of slag shot and acting to shield subsequent heat absorbing surfaces from the primary furnaces, a convection section including a bank of upright steam generating tubes and a bank of upright superheater tubes disposed rearwardly of said platten, and lower headers disposed along the sides of the installation in the zone of the convection section, the tubes of said convection section having their lower parts bent outwardly for direct connection with said last mentioned headers.

14. In a fluid heat exchange installation, a furnace having its boundary surfaces defined by fluid conducting tubes, burners, means supplying pulverized fuel and air to the burners for firing the furnace at temperatures above the fusion temperature of the non-combustible residue of the fuel, said boundary surfaces including a floor receiving said residues to form a molten slag layer, the furnace floor being provided with a slag discharge opening, a slag clearer including a member normally movable into said slag discharge opening to clear away solidified slag which tends to close said opening, a convection section heated by the furnace gases, and a bypass construction including conduit means causing some of the furnace gases to pass through said opening and join the remainder of the gases at a position rearwardly of the convection section.

15. In a furnace having an opening at its lower

part for the discharge therethrough of molten slag, means firing the furnace with a slag forming fuel at temperatures above the fusion temperature of the slag, a slag clearer having a part constructed and arranged to impact and remove slag bodies accumulated at said opening, means for movably mounting said part externally of and beneath the furnace, and means for moving said part upwardly toward said opening and across the path of slag flow downwardly from said opening.

ERVIN G. BAILEY.
